FRAME ASSEMBLY FOR BALANCING MACHINE

Fred R. Bokorney, Hillside, Ill.

Application December 7, 1956, Serial No. 44,106

Term of patent 7 years

(Cl. D52—1)

FIG. 1.

FIG. 2.

FIG. 3.

FIG. 4.

Fig. 1 is a perspective view of a frame assembly for balancing machine, showing my new design.

Fig. 2 is a cross-sectional view through the longitude thereof;

Fig. 3 is a frontal perspective view thereof; and

Fig. 4 is a plan view thereof with a minor corner portion broken away for the sake of enlargement.

The dominant features of the design reside in the frame shown in full lines. The dotted line portions are omitted in Figs. 2 and 4 for convenience of illustration.

I claim:

The ornamental design for a frame assembly for balancing machine, as shown and described.
